UNITED STATES PATENT OFFICE.

WILLIAM H. DENSLow, OF WAVERLY, NEW YORK.

HEATER.

SPECIFICATION forming part of Letters Patent No. 781,500, dated January 31, 1905.

Application filed March 24, 1904. Serial No. 199,803.

To all whom it may concern:

Be it known that I, WILLIAM H. DENSLow, a citizen of the United States, residing at Waverly, in the county of Tioga and State of New York, have invented new and useful Improvements in Heaters, of which the following is a specification.

This invention relates to hot-air heaters or furnaces especially adapted for domestic use; and the primary object of the same is to provide simple and effective means between the upper terminal of the ordinary fire-pot and the lower end of the shell or inclosure forming the combustion-chamber to increase the dimensions of the fire-pot in a vertical direction and permit a variation in the depth of the fire-bed to accommodate changes in temperature by proportionately increasing the heating capacity of the furnace and to prevent injury to and burning out of the lower extremity of the combustion-chamber shell or inclosure by removing the latter as far as possible from the greatest point of heat, this position of the lower extremity of the shell or inclosure forming the combustion-chamber being also conducive to a uniformity in the expansion and contraction of said inclosure.

A further object is to generally improve the construction and efficiency of heaters of the class to which the invention relates and utilize the products of combustion or smoke at the upper extremity of the combustion-chamber for heating air fed to the furnace and passing into the lower part of the outer casing with more effectiveness before entrance into the flues without requiring the consumption of more fuel than is ordinarily used in devices of this class.

With these and other objects and advantages in view the invention consists in the construction of parts and their combined arrangement, which will be more fully herein-after set forth.

In the drawings, Figure 1 is a transverse vertical section through a heater or furnace embodying the features of the invention. Fig. 2 is a horizontal section taken in the plane of the line 2-2, Fig. 1.

Similar numerals are employed to designate corresponding parts in both views.

The numeral 1 designates a base of suitable contour and having an opening 2 therethrough, the said base supporting a fire-pot 3 and ash-pit 4, included in the lower portion of the heater. A grate 5 of any suitable form is disposed in the upper portion of the ash-pit below the lower terminal of the fire-pot, and from said ash-pit a conduit 6 extends outwardly to a door 7, covering an opening 8 in the lower extremity of an outer casing 9. The outer casing is constructed of suitable sheet metal, as usual, and has a top closure 10 and as many collars 11 as may be desired for the attachment of hot-air flues. A shaker rod or bar 12 from the grate 5 projects outwardly through the conduit 6 and is accessible through the door 7. The ashes from the pit 4 may also be removed through the conduit 6 and door 7.

The fire-pot 3 is strengthened by a series of external ribs 13, which increase in outward extent toward the upper extremity of said pot, where a flange or outwardly-projecting ledge 14 is formed and peripherally surrounded by an upstanding guard 15. On the ledge 14 a suitable cast-metal hollow ring 16 is disposed and has an open bottom closed by said ledge. This ring provides a dead-air chamber at the upper terminal of the fire-pot and also serves as a vertical extension for the latter. The outer wall 17 of the ring is vertically straight, and the lower extremity of said wall bears against the inner surface of the guard 15. The ring also has a reduced horizontally flat top 18, provided with an upstanding guard-flange 19, at a short distance from the periphery thereof, to provide an angular seat to receive the lower terminal of the shell or casing 20, forming the combustion-chamber 21. From the inner terminal of the top 18 the inner wall of the ring slopes downwardly at an angle of inclination toward the center of the fire-pot, as at 22, and continues into a short vertical wall 23, having its inner surface flush with the similar surface of the fire-pot 3. It will be seen that the ring 16 or the dead-air chamber provided thereby locates the lower terminal of the shell or casing 20 at a distance above the upper terminal or ledge 14 of the fire-pot 3, and by this disposition or arrange-

ment of the shell or casing 20 injury to or 5 burning out of the lower terminal thereof is obviated and a regular expansion and contraction of said shell or casing ensues, thus avoiding the formation of open joints between the parts directly coöperating with the fire-pot. An open joint between the ledge 14 and the lower open side or bottom of the ring 16 is avoided by reason of the inner and outer walls 10 of said ring engaging or resting on the ledge at a distance from each other, and tendency to burning out of the ring 16 will also be prevented by reason of the dead-air chamber provided thereby. The fire-bed capacity of 15 the heater or furnace is also materially increased by the interposition of the ring 16 between the fire-pot and the shell or casing of the combustion-chamber, and the heater in moderate weather may have a fire-bed therein 20 of limited vertical extent, or in very cold weather the fire-bed may project upwardly to the top of the ring without liability of injury to the shell or casing of the combustion-chamber. This is an important feature in furnace 25 construction, as the heating capacity of furnaces having fire-pots of ordinary dimensions may be materially increased without modifying the remaining dimensions of furnaces. It will also be understood that the inner inclined portion 22 of the ring 16 effectively 30 serves in directing the fuel into the fire-pot, and the narrow top 18 will reduce the tendency of the fuel to lodge thereon.

The shell or casing 20 has a dome-shaped 35 cap 24, with a central enlarged opening 25 and smaller openings 26 in concentric relation thereto, the said openings 25 and 26 being surrounded by upstanding collars 27 and 28, respectively. A closed dome 29 is fitted over 40 the collar 27, and engaging the collars 28 are lower reduced tubular necks 30, depending at regular intervals from the bottom 31 of an annular chamber 32. The dome 29 projects upwardly through the central open space 33 45 of the annular chamber 32 and forms, with the latter, an annular passage, the bottom 31 of the said chamber being high enough above the cap 24 to permit the air to pass under the bottom of said chamber 32 and upwardly 50 through the annular passage 33. There is no means of communication between the dome 29 and the passage 32, and the latter communicates with the smoke-flue collar 34, secured to the upper part of the outer casing 9 through 55 the medium of a short flue 35, opening into the chamber 32 and having a damper 36 hinged at its upper end thereto and operative by means of a slideable rod 37, connected to the lower portion thereof and projecting outwardly through the outer wall of the chamber 32 and the outer casing 9.

The combustion-chamber 21 has a fuel-chute 38 leading thereto at a downward angle of inclination and terminating at its upper outer portion coincidently with an open-

ing 39 in the casing 9, the said opening being rendered accessible through the medium of a suitable door 40.

The products of combustion or smoke rising from the fire-pot and entering the combustion-chamber 21 pass from the latter into the dome 29 and the chamber 32, and the air fed into the bottom of the outer casing 9, through the medium of a suitable air-chute 41, is fully heated by coming in contact with the outer and inner walls of the chamber 32 and the said dome 29. It will be observed that the air passing between the bottom of the chamber 32 and the cap 24 will be heated by said cap, as well as the bottom, and the heat of the air passing between the bottom of the chamber 32 and the cap 24 will be intensified by passing upwardly through the annular passage 33 and rendered more effective as a heating medium when it passes through the top 10 of the outer casing 9 into the hot-air flues. Through the medium of the damper 36 the draft may be regulated in such manner as that the smoke and products of combustion may be checked in any tendency 90 toward rapidly passing off into the smoke-flue before the full heating effect thereof has been obtained without in the least impairing the necessary draft, and particularly will this be so when high winds are blowing and the 95 uptake and suction in the smoke pipe or flue is increased above normal. Sufficient circulation of the smoke and products of combustion in the dome 29 will be set up by the draft of the furnace to allow new charges to 100 successively replace each other therein, the smoke and products of combustion from the dome passing into the chamber 32 through the openings 26. This auxiliary heating attachment is very effective in the operation of 105 the improved heater or furnace, as a greater heating-surface is provided. Moreover, the use of fuel is economized.

Changes in the proportions, dimensions, form, and minor details may be resorted to 110 without departing from the spirit of the invention.

Having thus described the invention, what is claimed as new is—

A heater comprising an outer casing having a top closure, a fire-pot in the casing having an outwardly-projecting ledge at its upper end, an upstanding guard surrounding the ledge, external ribs on the fire-pot increasing in upward extent toward their upper ends and bracing the ledge, a hollow ring having an open bottom resting upon the ledge inside the guard, said ring having a vertical outer wall, a reduced horizontal flat top provided with an upstanding guard-flange and an inner wall inclined downwardly and terminating in a short vertical wall resting on the inner periphery of the ledge, a shell or combustion-chamber resting upon the hollow ring outside the guard-flange thereof, a dome-shaped cap 130

on the combustion-chamber, an annular chamber above the cap and below the top closure of the outer casing, tubular necks connecting the annular chamber with the shell, a dome 5 surrounded by the annular chamber and communicating with the combustion-chamber, and a hot-air outlet over the annular chamber.

In testimony whereof I affix my signature in presence of two witnesses.

WILLIAM H. DENSLOW.
